Baldwin Dale
ATTORNEY.

UNITED STATES PATENT OFFICE.

MARTIN FLATLAND, OF SAN FRANCISCO, CALIFORNIA.

ELECTRIC SWITCH-BOX.

1,314,259.

Specification of Letters Patent. Patented Aug. 26, 1919.

Application filed March 20, 1917. Serial No. 156,176.

To all whom it may concern:

Be it known that I, MARTIN FLATLAND, a citizen of the United States, and a resident of the city and county of San Francisco, State of California, have made a new and useful invention, to wit: Improvement in Electric Switch-Boxes; and I do hereby declare the following to be a full, clear, concise, and exact description of the same.

10 This invention is an improved safety switch for electric circuits, which may be swung open to break the circuit without exposing the live parts and which when open is prevented from accidentally closing and 15 is prevented from being closed at all except in such way as to prevent exposure of the switch contacts.

In this specification and the annexed drawing I illustrate the invention in the 20 form which I consider the best, but it is to be understood that I do not limit myself to such form because said invention may be embodied in other forms, and it is also to be understood that in and by the claims following the description, I desire to cover the 25 invention in whatever form it may be embodied.

Referring to the accompanying drawings:

Figure 1 is a vertical longitudinal section 30 of the switch in closed position.

Fig. 2 is a plan view of the switch in open position.

Fig. 3 is a plan view of a portion of the switch showing the means for locking the 35 switch closed and for preventing access to the live parts of the switch.

In the drawing 1 indicates a box having a cover 2, hinged at 3. In the bottom of the box is secured an ordinary knife switch circuit closer 4, comprising an insulating base 5, terminals 6, mounted on the base, knife members 7 pivoted at 8 to the terminals 6, insulating handle bar 9, handle 10, and contacts 11 mounted on the base, into which 45 contacts the knife members engage to close a circuit, the leads of which are to be connected to said terminals and contacts. Fuse sockets 12 may be mounted on the base and interposed in the circuit leads connected to 50 the respective terminals 6.

The cover of the box is provided with a longitudinal slot 15, through which the han-

dle 10 is adapted to project, the end of which slot is enlarged at 16 to permit the handle ring 17 to pass through the cover.

A lock and closing bar 20 is pivoted at one end at 21 to the underside of the cover 2, the other end of which is provided with an arcuate slot 22 struck from the center of pivot 21 through which slot extends a screw 23 which screws into the cover 2 and its head engages the under side of the bar and holds the end thereof against the underside of the box cover. The end of the bar near its pivot is provided with a notch 24 to receive the upper end of switch handle 10 when the switch is closed and a lug 25 is formed on the bar at the end of the notch which is adapted to be engaged by the switch handle 10 when the switch is closed, whereby the 70 bar is swung on its pivot under the slot 15, closing said slot, and the end of the bar is swung under a lug 26 on the body of the box holding the cover in closing position on the box and the switch closed.

A weighted swinging insulating member 30 is pivotally mounted on a rod 31 mounted in the walls of the box, which member extends entirely across the box above the switch contacts 11 and is provided with a 80 slot 32 through which the switch handle 10 may extend when the switch is closed. A lug 35 secured to the underside of the cover 2 engages the rear part of the member 30 when the cover is closed, and holds the forward end of the member up above the contacts 11 so that the switch knife members 7 may be swung down into, or up out of said contacts.

When the switch is opened and the cover 90 is raised to permit access to the switch, the lug 35 disengages the member 30 and the forward end of the member drops, under the influence of its weight, down upon the contacts 11 and prevents exposure of the 95 contacts and closing of the switch until the cover is swung closed. When the switch cover is closed the lug 35 engages and swings the insulating member up above the contacts and allows the switch to be closed.

Upon swinging the handle 10 to open the switch, said handle engages the forward inclined end of the notch 24 and swings the bar 20 on its pivot from under the slot so

that the handle may swing through the slot and disengage the end of the bar from the lug 26, unlocking the cover 2.

When the cover and switch are closed the 5 bar 20 prevents access through the slot 15 to the live parts of the switch and when the switch and cover are open the member 30 covers the contacts 11 and prevents closing of the switch.

10 The cover is formed with embossments 40 for engaging pins 41 on the handle 10 and holding the circuit closer in closed position. A little pressure applied to the handle knob 17 will disengage the pins from 15 the embossments. A hasp 45 is pivoted at 46 to the top of the cover 2, which hasp is slotted to slip over the handle ring 17 and a lock 50 is locked in the ring whereby the switch is locked in open position with the 20 cover in closing position and the parts in closed.

Having thus described my invention, I claim as new and desire to secure by Letters Patent:

25 1. A device of the character described comprising a box; a circuit closer in said box; a cover on said box provided with a slot; said cover being adapted to open when the circuit closer is in open position; a handle 30 for actuating said circuit closer adapted to project through said slot when the circuit is closed; means for locking the cover closed on the box when the switch is closed and for closing said slot when the circuit is 35 closed.

2. A device of the character disclosed comprising a box, a circuit closer in said box, a cover on said box, a weighted insulating swinging member pivoted in the box and 40 adapted to cover the parts of the circuit closer by which the circuit is closed, when the circuit is open, and means on the cover for engaging and swinging said member up when the cover is closed to permit the circuit closer to close.

3. A safety switch comprising a box, a cover for said box provided with a slot, a circuit closer in said box, a handle for operating said circuit closer, said handle projecting through said slot, and means positioned exteriorly of said box engaging said handle for locking the switch open.

4. A safety switch comprising a box, a cover hinged to said box, said cover being 55 provided with a slot, a circuit closer in said box, a handle for operating said circuit closer, said handle projecting through said slot when the cover closes said box, and means positioned exteriorly of said box engaging said handle for locking the switch open.

5. A safety switch comprising a box, a cover for said box, a circuit closer in said box, a handle for operating said circuit 60 closer, said handle projecting through said

slot, contact covering means to prevent closing of the switch contacts when the switch and cover are open, means whereby said contact covering means is thrown away from said contacts when said cover is closed to permit closing of the switch.

6. A safety switch comprising a box, a cover for said box, a circuit closer in said box, a handle for operating said circuit closer, said handle projecting through said slot, contact covering means to prevent closing of the switch contacts when the switch and cover are open, means whereby said contact covering means is thrown away from said contacts when said cover is closed to 70 permit closing of the switch, and means for locking said cover closed and said circuit closer open.

7. A safety switch comprising a box, a cover for said box provided with a slot, a circuit closer in said box, a handle for operating said circuit closer, said handle projecting through said slot, a hasp on said cover for engaging said handle when the switch is open, and a lock engaging said 80 handle whereby the switch is locked in open position.

8. A safety switch comprising a box, a cover for said box provided with a slot, a circuit closer in said box, an operating handle for said circuit closer projecting through said slot, and means operated by said handle for locking said cover closed when the switch is closed and for closing said slot.

9. A safety switch comprising a box, a cover for said box provided with a slot, a circuit closer for said box, an operating handle for said circuit closer projecting through said slot, a locking bar pivoted on the underside of said cover, a lug on the box, and 105 a part on said bar engaged by said handle when the switch is closed to swing said bar under said lug to lock the cover on the box.

10. A safety switch comprising a box, a cover for said box provided with a slot, a circuit closer in said box, an operating handle for said circuit closer projecting through said slot, a locking bar pivoted on the underside of said cover, a lug on the box, and a part on said bar engaged by said handle 115 when the switch is closed to swing said bar under said lug and across said slot to lock said cover closed and to close said slot.

11. A safety switch comprising a box, a cover for said box provided with a slot, a circuit closer in said box, an operating handle projecting through said slot, a pin on said handle and an embossment on said cover for engaging said pin to hold the switch closed.

12. A safety switch comprising a box, a cover for said box provided with a slot, a circuit closer for said box, an operating handle for said circuit closer, projecting through said slot, a locking bar pivoted on 130

the under side of said cover, a lug on the box, and a part on said bar engaged by said handle when the switch is closed to swing said bar under said lug to lock the cover on the box, and means for holding the switch closed.

In testimony whereof, I have hereunto set

my hand at San Francisco, California, this 8th day of March 1917.

MARTIN FLATLAND.

In presence of—

BALDWIN VALE,

A. J. HENRY.
